UNITED STATES PATENT OFFICE.

GEORGE A. TRANSUE, OF FACTORYVILLE, PENNSYLVANIA.

HAND ADDRESSING-MACHINE.

1,005,367.

Specification of Letters Patent. Patented Oct. 10, 1911.

Application filed September 20, 1910. Serial No. 582,937.

To all whom it may concern:

Be it known that I, GEORGE A. TRANSUE, a citizen of the United States, residing at Factoryville, in the county of Wyoming and State of Pennsylvania, have invented new and useful Improvements in Hand Addressing-Machines, of which the following is a specification.

This invention relates to a hand addressing machine, and the primary object of the same is to provide a machine of this class adapted for the use of type plates and wherein the said plates may be readily and quickly applied and used, and withdrawn or changed during progressive addressing work by a simple manipulation.

The invention consists essentially of a manually operated slide constructed to receive a type plate which is moved under an inked ribbon disposed below an impression effecting device, the ribbon being regularly shifted by the movement of the slide.

The invention further consists of the details of construction and arrangement of parts which will be more fully hereinafter described and claimed.

The drawings illustrate a typical embodiment of the invention for the purpose of practical demonstration. The invention, however, is not limited to the exact structure or application shown, and it will be understood changes may be made within the scope of the claims.

In the drawings: Figure 1 is a perspective view of an addressing machine embodying the features of the invention. Fig. 2 is a view of the machine partly in side elevation and partly in longitudinal section. Figs. 3 and 4 are detail views of one of the type plates. Fig. 5 is a sectional side elevation showing the parts of the machine in position when an impression is made. Fig. 6 is a bottom plan view of the top of the machine and ribbon holding and feeding means.

Fig. 7 is a transverse vertical section of the machine taken in advance of and close to the ribbon spools. Figs. 8 and 9 are detail views of portions of ribbon mechanism. Fig. 10 is a detail side elevation of the impression head. Fig. 11 is an enlarged transverse vertical section through the impression head. Figs. 12 and 13 are detail perspective views of parts of the impression head. Fig. 14 is a detail perspective view of the type plate carrying slide.

The numeral 5 designates a suitable bed

having a base 6 and flat top 7 with a slot 8 therein. At one end of the bed an impression lever 9 is fulcrumed and normally held elevated by a suitable torsion spring 10 engaging the same. An impression head 11 is carried by the free end of the lever 9 and includes a transverse socket 12 having a grooved finger grip or engaging means 13 secured to its front edge. Within the socket 12 an upper leveling plate 14 is adjustably mounted and is provided with a central rib 15 fitted in the groove of the socket and held by a clamping screw 16 loosely extending through the center of the socket. Adjacent to its opposite ends the rib 15 is engaged by leveling screws 17 for regulating the position of the pad. The plate 14 is centrally grooved as at 18 to receive the fulcrum rib 19 of the lower leveling plate 20 which is secured to the support 14 by screws 21, see particularly Figs. 10, 11, 12 and 13. Within the under side of the plate 20 a suitable rubber pad 22 is held and may be renewed when found necessary. The pad 22 is of such width and length as to effectively coöperate with the type plate below from which the impression is to be made, as will be hereinafter described.

Within the slot 8 of the top of the bed a type plate slide 23 is mounted, the side walls of the slot having ledges 24 on which the slide has loose bearing. The slide 23 is shorter than the length of the slot 8 and has its upper surface a sufficient distance below the surface of the top 7 of the bed 5 to permit the said slide to move under the ribbon. The front end wall of the slot 8 at the center has a finger depression 25 to permit the operator to engage or grasp the front edge of the slide. The rear extremity of the slide has a type plate seat formed in the upper side thereof and consisting of two transverse grooves 26 to receive the side flanges 27 of the type plate 28, see Figs. 3 and 4, and between said grooves a flat rest 29 is formed to receive the body of the type plate between the flanges 27. The rear extremity of the slide is reduced in thickness adjacent to the type plate seat, so as to give the plate proper position when applied relatively to the ribbon. The rear end 30 of the slide is also beveled downwardly to cause it to readily pass under the ribbon. To assist in the rapid application and withdrawal of a type plate, the slide at the front central portion of the seat has a finger opening 31 to

permit an operator to readily grasp the front edge of the type plate.

On the bed top 7 in the rear of the rear end wall of the slot 8, a gage 32 is adjustably secured to properly position the matter to be addressed. The top of the bed on opposite sides of the rear portion of the slot 8 is formed with two shorter slots 33 in transverse alinement for movement of the inked ribbon 34 therethrough transversely over the slot 8. This ribbon 34 is operated and carried by two spools 35 movably held within the bed 5 under the rear portion of the bolt 8 and having longitudinally disposed spindles or shafts 36 engaging hangers 37. The spools rotate with the spindles or shafts 36, the latter having on their rear ends nuts 37' and on their forward ends gears 38, one on each. A reverse gear shaft 39 is also mounted in the bed in hangers 40 in advance of the spools and their shafts, and is shiftable to bring the two reverse gears 41 thereon alternately in engagement with the gears 38 to change or reverse the movement of the ribbon on the spools. The shaft 39 is maintained in either one of its adjusted positions by a lock pawl 42, see Figs. 8 and 9, movably mounted close to one side of the bed to engage either one of two circumferential grooves 43 formed in one extremity of the shaft 39. This operation will be readily understood, as the structure is well known. Between the gears 41, a ribbon feed ratchet 44 is mounted on the shaft 39 and is engaged and operated by a pawl 45 mounted on the under portion of the forward extremity of the slide 23, said pawl being supported by lugs 46 and always held in true position to register with and operate the ratchet 44 by a cross pin 47 also held by the said lugs 46.

In the operation of the machine the slide 23 is drawn back to its full limit and then one of the type plates 28 is properly disposed in the seat thereof and the slide is pushed forward to bring the type plate fully under and close to the ribbon 34. The envelop or other matter to be addressed is then placed face down on the ribbon over the type plate on the slide. Then place fingers of hand on the grip or engaging means 13 and impart thereto a quick pressure to cause the head 11 and lever 9 to lower against the resistance of the spring 10 and to bring the said head 11 in firm contact with the envelop or other matter through the medium of the rubber pad 22 which covers the space of the type plate and effects an impression therefrom. Then release the fingers from the grip 13 and the lever 9 returns to normal position. Return the slide to its forward or original position by grasping the central portion of the forward edge thereof, and then remove the type plate 28 by engaging the forward

plate edge with the thumb and index finger through the opening 31 and remove the plate and apply another, and so on in accordance with the number of envelops or other matter desired to be addressed. At each movement of the slide 23 toward the ribbon to place the type in proper position, the pawl 45 acts on the ratchet 44, and the ribbon is proportionately shifted. When the ribbon has fully run off one spool onto the other, the reversing gear shaft 39 is shifted and the ribbon correspondingly reversed in its feeding movement.

The improved addressing machine will be found very convenient in its use, and may be rapidly operated to expeditiously address a large amount of matter in a short time.

What is claimed is:

1. In an addressing machine, a bed having a ribbon, a manually operated impression device disposed over the ribbon, and a slide mounted in the bed and having a type plate movably applied to the top portion of its forward extremity and movable under the ribbon, the slide having a reciprocating movement imparted thereto and operative independently of the impression device, the slide always being free for reciprocating operation, the matter to be printed being placed on the ribbon over the said forward extremity of the slide for engagement by the impression device.

2. In an addressing machine, a bed having a ribbon transversely movable thereover and an impression device disposed over the ribbon and having a self-elevating operation when released, a slide operative independently of the impression device and provided with a seat in the upper portion of the forward extremity thereof, the slide having a reciprocating operation, and a type plate removably mounted in the seat and movable with the slide under the ribbon.

3. In an addressing machine, a bed having a ribbon, an impression device disposed over the ribbon and having a depressing operation, and a type plate carrying slide mounted in the bed and having a reciprocating operation and freely movable forwardly under and rearwardly from beneath the said ribbon independently of the operation of the impression device.

4. In an addressing machine, an impression imparting ribbon provided with feeding means, an impression device disposed over the ribbon and having a depressing operation, and a type plate carrying slide freely movable under and from beneath the ribbon and having means to engage a portion of said ribbon feeding means to shift the ribbon, the slide being free for reciprocating movement independently of the operation of the impression device.

5. In an addressing machine, an impression imparting ribbon movable thereover and

- provided with feeding means, an impression device disposed over the ribbon and having a depressing movement with relation to the latter, and a manually operated type plate carrying slide free for reciprocation forwardly under and rearwardly from beneath the ribbon independently of the impression device and having projecting means to engage a portion of the said ribbon feeding means for causing the ribbon to shift.
6. In an addressing machine, a bed, an impression lever thereon having a head, an upper leveling plate adjustably fitted in the head and provided with a lower longitudinal central groove, a lower leveling plate having an upper fulcrum rib engaging the said groove and adjustably connected to the upper leveling plate and carrying a yielding pad, a ribbon with which the head and leveling plates coöperate, and a type plate carrying slide freely reciprocable in the bed under and outwardly from the ribbon and operative independently of the lever.
7. In an addressing machine, the combination with a bed having a ribbon and an impressing device, of a rigid slide mounted in the bed to move under the ribbon, the impressing device and slide being manually and independently operative, and the slide being formed with transverse grooves in its upper side separated by a raised flat rest,

and a type plate having side flanges and a flat body to respectively engage the grooves and rest.

8. In an addressing machine, the combination with a bed having a ribbon and an impressing device, of a slide mounted in the bed to move under the ribbon and formed with transverse grooves in its upper side separated by a flat rest and also provided with an opening centrally positioned with relation to one groove, and a type plate having side flanges and a flat body to respectively engage the grooves and rest.

9. In an addressing machine, the combination with a bed having a slot in the top thereof, a ribbon extending across the rear portion of said slot, an impressing device operable over the ribbon, and a type plate slide of less length than and movable in the slot to move a type plate carried thereby under and outwardly from the said ribbon, the impressing device and slide being independently and manually operative.

In testimony whereof I have hereunto set my hand in presence of two subscribing witnesses.

GEORGE A. TRANSUE.
